UNITED STATES PATENT OFFICE

97,827

DESIGN FOR A PHOTOELECTRIC EXPOSURE METER

Edward F. Weston, Elizabeth, N. J., assignor to
Weston Electrical Instrument Corporation,
Newark, N. J., a corporation of New Jersey

Application September 12, 1935, Serial No. 58,536

Term of patent 7 years

To all whom it may concern:

Be it known that I, Edward F. Weston, a citizen of the United States, residing at Elizabeth, in the county of Union and State of New Jersey, have invented a new, original, and ornamental Design for a Photoelectric Exposure Meter, of which the following is a specification, reference being had to the accompanying drawing, forming part thereof, and wherein:

Fig. 1 is a front view of a photoelectric exposure meter showing my new design;

Fig. 2 is an end view thereof; and

Fig. 3 is a rear view.

In the drawing, the dotted lines of Fig. 3 indicate a light-admitting opening which is opposite the computer that is indicated by dotted lines at the left of Fig. 1. The computer is employed for translating readings of light values, as taken from the measuring scale shown at the upper right of Fig. 1, into terms of exposure data.

I claim:

The ornamental design for a photoelectric exposure meter, as shown and described.

EDWARD F. WESTON,
